(57) **CLAIM**

The ornamental design for a blending apparatus as shown and described.

DESCRIPTION

FIG. 1 is a front perspective view of a blending apparatus; FIG. 2 is a front view thereof; FIG. 3 is a rear view thereof; FIG. 4 is a right side view thereof; FIG. 5 is a left side view thereof; FIG. 6 is a top view thereof; and, FIG. 7 is a bottom view thereof.

The broken lines immediately adjacent to the shaded area define the bounds of the claimed design and form no part thereof. The broken lines depicting the remainder of the blending apparatus form no part of the claimed design.

1 Claim, 6 Drawing Sheets
